ABSTRACT

A paper scrap pushing structure of a paper shredder, having a paper pushing unit, with a spindle having a longitudinal axis, a spindle flap coupled along the longitudinal axis to the spindle; and a paddle pushing segment, coupled to the spindle flap. The spindle is arranged under a paper outlet of the paper shredder and is in linkage with a paper shredder cutter shaft through a synchronous transmission device. When the rotating shaft rotates, the rotating shaft drives the paddle pushing segment to move in the circumferential direction along with the spindle flap, removing paper scraps at the top of a paper scrap pile in a shredded paper waste bin.

PAPER SCRAP PUSHING STRUCTURE OF
PAPER SHREDDERCROSS-REFERENCE TO RELATED
APPLICATIONS

The present application is a continuation-in-part of the U.S. patent application Ser. No. 17/133,606 filed on Dec. 23, 2020, published under the publication number US 2021/0114040 A1 and entitled "Paper Scrap Pushing Structure of Paper Shredder", which is a continuation-in-part of U.S. patent application Ser. No. 15/885,410, filed Jan. 31, 2018, entitled "Paper Scrap Pushing Structure of Paper Shredder", which issues as U.S. Pat. No. 10,875,029 on Dec. 29, 2020, all of which prior applications are incorporated herein in their entirety.

BACKGROUND OF THE EMBODIMENTS

1. Technical Field

The embodiments relates to the technical field of paper scrap processing of paper shredders, in particular to a paper scrap pushing structure of a paper shredder.

2. Description of Related Art

Paper shredders are machines used for processing paper scraps and can cut waste paper into strip-shaped or granular paper scraps; however, the strip-shaped or granular paper scraps can be locally stacked in shredded paper waste bins without being processed, subsequent paper scraps cannot fall down smoothly due to piled paper scraps, and consequentially the paper scraps overflows out of the shredded paper waste bin soon, affecting the overall operating function of the paper shredder.

Previously, swinging mechanisms were used for making paper scraps fall into shredded paper waste bins in a swinging mode. For example, a swinging paper shifting mechanism at a paper falling port of a paper shredder is disclosed by the embodiments patent with the Chinese patent application No. CN200720000902. Here, the swinging paper shifting mechanism includes a motor and a cutter assembly provided with a transmission gear and arranged in a case. A waste paper waste bin used for collecting paper scraps is arranged below the cutter assembly. The mechanism also includes a swinging plate arranged near the paper falling port of the case and connected with a transmission shaft through a connecting rod. A driven gear is arranged at one end of the transmission shaft and receives power from the cutter assembly to rotate. The transmission shaft drives the swinging plate to reciprocate forward and backward through the connecting rod when rotating, paper scraps evenly falls down into the waste paper waste bin from a cutter shaft and are flatly piled up gradually, so that the space for containing paper scraps in the waste paper waste bin is increased. In this patent, the swinging plate can only reciprocate around the transmission shaft, and consequentially the transmission structures of the two sides of the transmission shaft are complex.

A uniform paper scrap shifting device of a paper shredder is disclosed by the embodiments patent with the Chinese patent application No. CN200920261627. In this patent, the uniform paper scrap shifting device includes a second swinging support, a swinging plate, a first swinging support, a swinging rod, a rotating shaft and an adjustable support, wherein one end of the rotating shaft is fixed to a paper

2

shredder cutter shaft and concentrically rotates along with the cutter shaft. The adjustable support is arranged at the other end of the rotating shaft. A convex column of the adjustable support is slidably sleeved with a guide rail trough, and the other end of the swinging rod is connected with the first swinging support through a D-shaped shaft hole. The second swinging support is fixed to the paper shredder. The two ends of the swinging plate are fixed to a swinging arm of the first swinging support and a swinging arm of the second swinging support respectively. In this patent, since the swinging plate is of an integral structure, only the side of the swinging plate, away from the rotating shaft, can be used for removing paper scraps, materials are wasted, and the structure is not simple.

15 A paper shredder is disclosed by the embodiments patent with the Chinese patent application No. CN200920274623. The paper shredder is provided with a positioned rotating device, which is adjacent to a discharging port of a paper shredder shell. The rotating device comprises a shaft, and the 20 shaft can rotate around an axis parallel to the axis of a cutting assembly so that the rotating device can rotate. The rotating device is provided with a plurality of finger parts which can at least partially extent in the radial direction from the shaft. The rotating device can rotate around the axis of the shaft in 25 any direction so that any accumulated shredded paper in a waste box can be dispersed and shredded paper collected in a cutting assembly adjacent to the discharging port or nearby can be removed. In this patent, because the finger parts are elastic and are relatively scattered, the scrap removal effect 30 is not ideal enough.

35 A paper scrap distribution device of a paper shredder is disclosed by the embodiments patent with the Chinese patent application No. CN201120214524. The paper scrap distribution device comprises distribution blades and a rotating shaft in linkage with a paper shredder cutter shaft. The distribution blades are arranged on the rotating shaft in the length direction. The number of the distribution blades is at 40 least two, with the plastic or metal distribution blades are arranged at intervals. A wheel disc in linkage with the paper shredder cutter shaft is arranged at one end of the rotating shaft. Alternately, a gear in linkage with the paper shredder cutter shaft is arranged at one end of the rotating shaft. A 45 housing can be mounted at a paper outlet of the paper shredder. The rotating shaft is rotatably arranged in the housing, and the bottom of the housing is open. In this patent, since the distribution blades are integral blades, only the parts, on the side away from the rotating shaft, of the blades can be used for removing paper scraps, materials are wasted, and the structure is not simple.

50 What is needed is a paper scrap pushing apparatus for a paper shredder that overcomes the above problems.

SUMMARY

55 For overcoming the shortcomings of the prior art, the embodiments herein provide a paper scrap pushing structure of a paper shredder. The paper scrap pushing structure of the paper shredder is clever in design, simple in structure, and practical in function. Also it has a better paper scrap distribution function and is suitable for large-scale application 60 and commercialization.

65 In embodiments, a paper scrap pushing structure of a paper shredder includes a rotating shaft, a paper pushing rod and a plurality of connecting rods, wherein the rotating shaft is arranged under a paper outlet of the paper shredder and is in linkage with a paper shredder cutter shaft through a synchronous transmission device. The paper pushing rod is

located on one side of the rotating shaft, arranged in the length direction of the rotating shaft in parallel, and connected with the rotating shaft through the multiple connecting rods. The distance from the paper pushing rod to the rotating shaft is generally smaller than the distance from the lowest portion of the paper shredder cutter shaft to the rotating shaft. A paper pushing unit is defined by the rotating shaft, the connecting rods and the paper pushing rod. When the rotating shaft rotates, the rotating shaft drives the paper pushing rod to move in the circumferential direction through the connecting rods so as to remove paper scraps at the top of a paper scrap pile in a shredded paper waste bin.

Furthermore, in an embodiment, included are the left connecting rod and the right connecting rod, with the left connecting rod and the right connecting rod being located at the respective ends of the paper pushing rod and the rotating shaft. In another embodiment, the left connecting rod and the right connecting rod are each of a telescopic structure, and springs are arranged at the ends, proximate to one end of the rotating shaft, of the left connecting rod and the right connecting rod.

Furthermore, in yet another embodiment, the number of the connecting rods is three, the three connecting rods are the left connecting rod, the middle connecting rod and the right connecting rod respectively. The left connecting rod, the middle connecting rod, and the right connecting rod are arranged between the paper pushing rod and the rotating shaft at generally equal intervals. In still another embodiment, the left connecting rod and the right connecting rod are each of a telescopic structure, and the middle connecting rod is of a sleeve structure. The springs are arranged at the ends, proximate to one end of the rotating shaft, of the left connecting rod and the right connecting rod. The middle connecting rod comprises an inner sleeve and an outer sleeve. The inner sleeve is perpendicularly connected with the rotating shaft, and the outer sleeve is perpendicularly connected with the paper pushing rod. In a further embodiment the inner sleeve is perpendicularly connected with the paper pushing rod, and the outer sleeve is perpendicularly connected with the rotating shaft.

In another embodiment, the paper pushing rod and the multiple connecting rods are formed integrally. In yet another embodiment, the paper pushing rod and/or the connecting rods are made of plastic or rubber or metal.

Embodiments of the paper scrap pushing structure of the paper shredder can further include two inverted U-shaped guide grooves oppositely arranged on the inner walls of side plates on the two sides of the paper shredder. Here, the paper pushing rod enters the inverted U-shaped guide grooves when rotating around the rotating shaft in the circumferential direction and is compressed to be prevented from colliding with the paper shredder cutter shaft above.

Moreover, the radial angle (radian) of each inverted U-shaped guide groove is decreased gradually, and the distance from the portion, with the smallest radian, of each inverted U-shaped guide groove to the center of the rotating shaft is slightly greater than the distance from the side, away from the rotating shaft, of the paper pushing rod to the center of the rotating shaft.

In an embodiment, the number of the paper pushing units is equal to or larger than two, and the paper pushing units are arranged in the circumferential direction of the rotating shaft at intervals.

In an embodiment, the paper pushing units are arranged in the circumferential direction of the rotating shaft at equal intervals.

In an embodiment, the synchronous transmission device includes a gear set, the two ends of the rotating shaft are connected with gear shafts arranged on the two sides of the paper shredder, and the rotating shaft is in synchronous linkage with the paper shredder cutter shaft through engaging movement of gears in the gear set.

In another embodiment, the synchronous transmission device includes a cutter shaft gears and rotating shaft gears, the cutter shaft gears are arranged at the two ends of the paper shredder cutter shaft, the rotating shaft gears are arranged at the two ends of the rotating shaft, and the cutter shaft gears are in synchronous linkage with the rotating shaft gears through a synchronous belt.

Furthermore, in some embodiments, a paper pushing unit 15 may be non-segmented; in yet other embodiments, the paper pushing unit may be segmented. A segmented paper pushing unit may include a spindle coupled to a spindle flap. The spindle flap may be joined by hinge pins to a paddle pushing 20 segment. The paddle pushing segment may move relative to the spindle flap, generally transversely to the longitudinal axis of the spindle. In still other embodiments, a spindle may be disposed at intervals with plural spindle flaps each 25 connected to a respective one of plural paddle pushing segment.

BRIEF DESCRIPTION OF THE DRAWINGS

For a clearer illustration of the technical scheme of the 30 embodiments of the embodiments, a brief description of the drawings required for illustration of the embodiment of the embodiments is given as follows. Obviously, the drawings in the following description are only for part of the embodiments of the embodiments, and for those skilled in the field, other drawings can also be obtained according to the drawings 35 without creative work. In the drawings:

FIG. 1 is a structural diagram of a paper pushing unit in the paper scrap pushing structure of the paper shredder of the 40 embodiments;

FIG. 2 is a diagram of the part and shape, at the paper outlet of the paper shredder, of the paper pushing unit in the paper scrap pushing structure of the paper shredder of the 45 embodiments;

FIG. 3 is a structural diagram of the paper pushing unit in the paper scrap pushing structure of the paper shredder of the 50 embodiments;

FIG. 4 is a structural diagram of a synchronous gear transmission device in the paper scrap pushing structure of the paper shredder of the 55 embodiments;

FIG. 5 is a forward structural diagram of the telescopic paper pushing unit in the paper scrap pushing structure of the paper shredder of the 60 embodiments;

FIG. 6 is an inverted structure diagram of the telescopic paper pushing unit in the paper scrap pushing structure of the 65 paper shredder of the embodiments;

FIG. 7 is a forward structural diagram of plural telescopic paper pushing units in the paper scrap pushing structure of the paper shredder of the 70 embodiments;

FIG. 8 is a structural diagram of a synchronous belt 75 transmission device in the paper scrap pushing structure of the paper shredder of the embodiments;

FIG. 9 is a structural diagram of a segmented paper pushing unit in the paper scrap pushing structure of the paper shredder of the 80 embodiments;

FIG. 10A is an exploded structural illustration of the 85 segmented paper pushing unit of FIG. 9, in accordance with the teachings of the embodiments;

FIG. 10B is a perspective joined structural illustration of the exploded segmented paper pushing unit of FIG. 10A;

FIG. 11A is a structural illustration of the segmented paper pushing unit of FIG. 10, having a paddle pushing segment disposed in a first rotated position in accordance with the teachings of the embodiments;

FIG. 11B is a structural illustration of the segmented paper pushing unit of FIG. 10, having the paddle pushing segment disposed in a non-rotated position in accordance with the teachings of the embodiments; and

FIG. 11C is a structural illustration of the segmented paper pushing unit of FIG. 10, having the paddle pushing segment disposed in a second rotated position in accordance with the teachings of the embodiments.

Some embodiments are described in detail with reference to the related drawings. Additional embodiments, features and/or advantages will become apparent from the ensuing description or may be learned by practicing the invention. In the figures, which are not drawn to scale, like numerals refer to like features throughout the description. The following description is not to be taken in a limiting sense, but is made merely for the purpose of describing the general principles of the invention.

DETAILED DESCRIPTION OF THE EMBODIMENTS

A clear and complete description and discussion of the technical scheme in the embodiments are given with the accompanying drawings as follows. Only several of the embodiments of the present invention are described, and all other embodiments obtained by those skilled in the field without creative work based on the embodiments are within the protected scope of the claims.

In general, when the paper shredder is in typical use, paper scraps generated after paper is shredded, fall down and form a paper scrap pile. When the paper scrap pile exceeds a certain height, the paper pushing units located below the paper outlet of the paper shredder can push the paper scraps at the top of the paper scrap pile to create a more even distribution of paper scraps in a shredder waste bin. The rotating gears and the cutter shaft gears of the paper shredder cutter shaft drive the paper pushing units, and the paper shredder cutter shaft, to rotate synchronously through the synchronous belt or through synchronized engagement of the gear set. As a result, the paper scraps are distributed orderly and can be evenly piled in the shredded paper waste bin, and thus the space utilization rate of the paper waste bin is effectively increased.

As is shown in FIGS. 1-6, the embodiments disclose a paper scrap pushing structure of a paper shredder having a rod configuration. The paper scrap pushing structure of the paper shredder includes rotating shaft 1, paper pushing rod 2, and plurality of connecting rods 3, in which rotating shaft 1 is arranged under a paper outlet of the paper shredder and is in linkage with a paper shredder cutter shaft 4 through a synchronous transmission device 9. Paper pushing rod 2 may be located on one side of the rotating shaft 1, arranged in parallel in the length direction of the rotating shaft 1, and connected with the rotating shaft 1 through plurality of connecting rods 3. In general, the distance from paper pushing rod 2 to rotating shaft 1 is smaller than the distance from the lowest portion of paper shredder cutter shaft 4 to rotating shaft 1. When rotating shaft 1 rotates, rotating shaft 1 drives paper pushing rod 2 to move in the circumferential

direction through the connecting rods 3, removing paper scraps at the top of a paper scrap pile disposed in a shredded paper waste bin.

In an embodiment, the number of connecting rods 3 is two, the two connecting rods 3 being left connecting rod 31 and right connecting rod 32 respectively. Left connecting rod 31 and right connecting rod 32 can be located at the ends of paper pushing rod 2 and rotating shaft 1, respectively. To achieve the paper scrap distribution effect, the two connecting rods 31, 32 are simple in structure and reasonable in design, and materials can be saved. In an embodiment, the left connecting rod 31 and the right connecting rod 32 can be each of a telescopic structure, with springs 7 being arranged at the ends proximate to an end of the rotating shaft 1, and to left connecting rod 31 and right connecting rod 32.

As is shown in FIG. 3, FIG. 5 and FIG. 6, in another embodiment, the number of the connecting rods 3 can be three, the three connecting rods can be left connecting rod 31, middle connecting rod 33 and right connecting rod 32, respectively. Left connecting rod 31, middle connecting rod 33, and right connecting rod 32 can be arranged between the paper pushing rod 2 and rotating shaft 1, for example, at equal intervals. By arranging the connecting rods at equal intervals, force borne by paper pushing rod 2 can be evenly distributed to the connecting rods 3 when paper pushing rod 2 operates, and thus the service life can be prolonged. In the embodiment, the connecting rods 3 can be connected with paper pushing rod 2 and rotating shaft 1, for example, by insertion, by riveting, or by welding. In an embodiment, left connecting rod 31 and right connecting rod 32 can be each of a telescopic structure, and the middle connecting rod 33 can be of a sleeve structure. Springs 7 can be arranged proximate to each end of rotating shaft 1, and on left connecting rod 31 and right connecting rod 32. Middle connecting rod 33 can include an inner sleeve 41 and an outer sleeve 42. Inner sleeve 41 can be perpendicularly connected with the rotating shaft 1, and outer sleeve 42 can be perpendicularly connected with paper pushing rod 2. In another embodiment, inner sleeve 41 can be perpendicularly connected with paper pushing rod 2, and outer sleeve 42 can be perpendicularly connected with rotating shaft 1.

As is shown in FIG. 5 and FIG. 6, in another embodiment, the paper scrap pushing structure further includes two inverted U-shaped guide grooves 8 oppositely arranged on the inner walls of side plates 10 on the two opposing sides of the paper shredder. The radial angle (radian) of each inverted U-shaped guide groove 8 can be decreased gradually, and the distance from the portion with the smallest radian of each inverted U-shaped guide groove 8 to the center of rotating shaft 1 can be slightly greater than the distance from the side away from rotating shaft 1 of paper pushing rod 2 to the center of rotating shaft 1. Paper pushing rod 2 enters inverted U-shaped guide grooves 8 when rotating around rotating shaft 1 in the circumferential direction. Springs 7 of left connecting rod 31 and right connecting rod 32, and sleeves 41, 42 of middle connecting rod 33, are gradually compressed along with the decrement of the radians of inverted U-shaped guide grooves 8, so that paper pushing rod 2 is prevented from colliding with paper shredder cutter shaft 4 above. After paper pushing rod 2 passes through inverted U-shaped guide grooves 8, springs 7 return to their prior state. Through the design of springs 7, the distance between rotating shaft 1 and paper shredder cutter shaft 4 can be further decreased easily, the space of the shredder paper waste bin, below rotating shaft 1, of the paper shredder is effectively increased accordingly, the size of the paper shredder can be further decreased on the basis that the

space of the shredded paper waste bin is not changed. The cost of the paper shredder and the space occupied by the paper shredder can be reduced indirectly.

In an embodiment, paper pushing rod 2 and plurality of connecting rods 3 can be formed integrally. Through the integral design, the firmness between the paper pushing rod and the connecting rods can be improved easily, and the paper pushing rod and the connecting rods are not prone to being separated after extended use. When rotating shaft 1, paper pushing rod 2, and connecting rods 3 are made of the same materials, rotating shaft 1, paper pushing rod 2, and connecting rods 3 can also be formed integrally.

Paper pushing unit 11 can include rotating shaft 1, paper pushing rod 2, and connecting rods 3. The number of paper pushing units 11 can be set freely and can be one or more. In embodiments, such as shown in FIG. 7, the number of paper pushing units 11 coupled to rotating shaft 1 is equal to or larger than two, and paper pushing units 11, 77 can be arranged at intervals in the circumferential direction of rotating shaft 1. For achieving a better paper scrap distribution effect, paper pushing units 11 can be arranged in the circumferential direction of the rotating shaft at equal intervals. In certain embodiments, the number of paper pushing units 11 can be plural, for example, two or four or six. FIG. 7 illustrates a second paper pushing unit 77 disposed on rotating shaft 1. However, it is not true that the more paper pushing units 11, 77 there are, the better the effect is; if excessive paper pushing units are provided, the material cost can be increased, the structure can more complex, and the paper scrap distribution efficiency may be low.

In embodiments, paper pushing rod 2, connecting rods 3, or both, can be made of plastic, or rubber, or metal. In an economical paper pushing device of a paper shredder, paper pushing rod 2 and connecting rods 3 preferably can be made of plastic, which is low in price and proper in hardness.

Rotating shaft 1 can be in linkage with paper shredder cutter shaft 4 in multiple ways. As is shown in FIG. 4, in one embodiment, synchronous transmission device 9 can be a gear set, the two ends of rotating shaft 1 can be connected with gear shafts arranged on the two sides of the paper shredder, and rotating shaft 1 can be in synchronous linkage with paper shredder cutter shaft 4 through engaging movement of gears in the gear set. In another embodiment, shown in FIG. 8, synchronous transmission device 9 includes cutter shaft gears 5 and rotating shaft gears 6. Cutter shaft gears 5 can be arranged at the two ends of paper shredder cutter shaft 4, rotating shaft gears 6 can be arranged at the two ends of rotating shaft 1, and cutter shaft gears 5 can be in synchronous linkage with rotating shaft gears 6 through synchronous belt 55.

Paper pushing unit 11 can be provided in multiple configurations. For example, paper pushing elements may be configured in a rod configuration or may be configured in a paddle configuration, in which the paper pushing element is characterized by a broad, flat blade. In addition to the foregoing embodiments of a non-segmented paper pushing unit 11 of FIGS. 1-8, paper pushing unit 22 may be segmented. FIG. 9 depicts shredder body 20 coupled by rotating shaft spindle 100 to segmented paper pushing unit 22, in a manner similar to the coupling of rotating shaft 1 to paper pushing unit 11 in FIGS. 1-6. FIG. 10A illustrates an exploded view of one possible configuration of a segmented paper pushing unit 22 in which rotating shaft spindle 100 may be joined to spindle flap 110, and which longitudinally extends in parallel with rotating shaft spindle 100. In this configuration, spindle flap 110 can be integrally joined with rotating shaft spindle 100, although such is not required and

other manners of joining are possible. Spindle flap 110 may be configured to couple with hinged paddle pushing segment 120 using a hinge pin 115 on each side of spindle flap 110. As indicated by assembled illustration FIG. 10B, when retained by hinge pins 115, hinged paddle pushing segment 120 is generally capable of rotating around the longitudinal axis of rotating shaft spindle 100. By rotating, spindle flap 110 and hinged paddle pushing segment 120 can cause the distribution of paper scraps (not shown), which may have accumulated unevenly in the paper shredder waste basket (not shown) during paper shredder operation. As with the embodiments of FIG. 7, there may be two or more segmented paper pushing units 22 disposed on spindle 100, typically spaced equally apart on spindle 100.

FIGS. 11A-C illustrate segmented paper pushing unit 22 with hinged paddle pushing segment 120 disposed in a first rotated position, in an unrotated position, and in a second rotated position, respectively as spindle 100 is rotated upon its longitudinal axis. During rotation of spindle 100, hinged paddle pushing segment 120 can move relative to spindle flap 110. In some embodiments, paper pushing unit 22 rotates around spindle 100. In yet other embodiments, spindle 100 can oscillate, causing paper pushing unit 22 to operate in a back-and-forth sweeping manner.

The above embodiments are only preferred specific embodiments of the invention, the protection scope of the embodiments is not limited to the above embodiments, and changes or substitutes which can be easily obtained by those skilled in the field within the technical scope disclosed by the embodiments should all be within the protection scope of the embodiments. Therefore, the protection scope of the embodiments is subject to the protection scope defined by the claims.

What is claimed is:

1. A paper scrap pushing structure of a paper shredder, comprising:
a paper pushing unit, including
a spindle having a longitudinal axis;
a spindle flap coupled along the longitudinal axis to the spindle; and
a paddle pushing segment, hingedly coupled to the spindle flap,
wherein the spindle is arranged under a paper outlet of the paper shredder and is in linkage with a paper shredder cutter shaft through a synchronous gear transmission device, and
wherein when the spindle rotates, the spindle drives the paddle pushing segment and the spindle flap in full-circle, unidirectional rotation in a circumferential direction about the longitudinal axis of the spindle, removing paper scraps at the top of a paper scrap pile in a shredded paper waste bin.
2. The paper scrap pushing structure of claim 1, wherein the spindle flap is integral with the spindle.
3. The paper scrap pushing structure of claim 1, wherein the paddle pushing segment is pinned to the spindle flap in a hinged arrangement.
4. The paper scrap pushing structure of claim 2, wherein the paddle pushing segment is pinned to the spindle flap in a hinged arrangement.
5. The paper scrap pushing structure of the paper shredder of claim 1, wherein at least one of the spindle, the spindle flap, or the paddle pushing segment is made of plastic, or of rubber, or of metal.
6. A paper scrap pushing structure of a paper shredder, comprising:
a spindle having a longitudinal axis;

a plurality of spindle flaps coupled to the spindle, spaced apart, and arranged in parallel to the longitudinal axis in the circumferential direction of the spindle at intervals; and

a plurality of paddle pushing segments, hingedly coupled to respective ones of the plurality of spindle flaps, wherein the spindle is arranged under a paper outlet of the paper shredder and is in linkage with a paper shredder cutter shaft through a synchronous gear transmission device, and

wherein when the spindle rotates, the spindle drives the plurality of paddle pushing segments and the plurality of spindle flaps in full-circle, unidirectional rotation in a circumferential direction about the longitudinal axis of the spindle, removing paper scraps at the top of a paper scrap pile in a shredded paper waste bin.

7. The paper scrap pushing structure of claim 6, wherein the plurality of spindle flaps is integral with the spindle.

8. The paper scrap pushing structure of claim 6, wherein each of the paddle pushing segments is pinned to a respective one of the plurality of spindle flaps in a hinged arrangement.

5 9. The paper scrap pushing structure of claim 7, wherein each of the paddle pushing segments is pinned to a respective one of the plurality of spindle flaps in a hinged arrangement.

10 10. The paper scrap pushing structure of the paper shredder of claim 6, wherein at least one of the spindle, the plurality of spindle flaps, or the plurality of paddle pushing segments is made of plastic, or of rubber, or of metal.

15 11. The paper scrap pushing structure of the paper shredder of claim 1, wherein the synchronous transmission device includes a gear set, wherein two opposing ends of the spindle are coupled to gear shafts arranged on two sides of the paper shredder, and wherein the spindle is in synchronous linkage with the paper shredder cutter shaft through engaging movement of gears in the gear set.
